UNITED STATES PATENT OFFICE.

WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO.

EXCAVATING-MACHINE.

1,398,195.

Specification of Letters Patent. Patented Nov. 22, 1921.

Application filed February 3, 1920. Serial No. 356,100.

To all whom it may concern:

Be it known that I, WILLIAM K. LIGGETT, a citizen of the United States, residing at Columbus, in the county of Franklin and

5 State of Ohio, have invented certain new and useful Improvements in Excavating-Machines, of which the following is a specification, reference being had therein to the accompanying drawing.

10 This invention relates to certain new and useful improvements in excavating machines, and especially to machines adapted to reclaim material from natural deposits or from storage piles, and to load said material into convenient receptacles for transportation.

One object of this invention is to provide a machine of the class described having an inclined conveyer especially adapted to

20 loosen and gather relatively compact material from a pile at the level of the ground, and to convey such material to elevated discharge points at the rear of the machine.

A further object is to provide a machine 25 of the class described having a conveyer adapted to clear itself when buried by the avalanching of the material of a storage pile.

A further object is to provide supporting 30 and controlling devices for the conveyer whereby it may be conveniently adjusted to various inclined operative positions, or to a horizontal position convenient for traveling under relatively low overhead obstructions.

35 A further object is to provide improved means for the attachment of the conveyer buckets to the conveyer chain adapting them to more efficiently gather, carry and discharge material.

40 A further object is to provide improved accumulating devices to receive the material from the continuously operating conveyer, and to discharge it at the option of the operator into suitably placed receptacles for 45 transportation.

The means by which I attain these, and other objects, are fully set forth in the following specification, reference being had to the accompanying drawings of which—

50 Figure 1 is a side elevation of the preferred embodiment of my invention showing the conveyer adjusted to an inclined position for gathering material from the ground.

Fig. 2 is a plan view of the machine illus-

trated in Fig. 1 certain of the parts being 55 broken away to reveal other parts.

Fig. 3 is a rear elevation of the machine illustrated in Fig. 1.

Fig. 4 is a side elevation of the machine illustrated in Fig. 1 showing the conveyer 60 adjusted to its horizontal position.

Fig. 5 is a horizontal transverse section of the power transmitting elements of the machine taken along the line V—V of Fig. 6.

Fig. 6 is a longitudinal vertical section of 65 the power transmission elements of the machine taken along the line VI—VI of Fig. 5.

Fig. 7 is a fragmentary detail of the operating handle of the reversing gear mechanism.

Fig. 8 is a fragmentary vertical cross section taken along the line VIII—VIII of Fig. 1.

Fig. 9 is a fragmentary end elevation of the devices illustrated in Fig. 8.

Fig. 10 is a cross section taken along the line X—X of Fig. 8.

Fig. 11 is a diagrammatic figure illustrating the action of the conveyer buckets when gathering material.

Fig. 12 is a diagrammatic figure illustrating the action of the conveyer buckets when discharging material.

Fig. 13 is a detail of the conveyer frame.

Figs. 14 and 15 are detail views of a conveyer bucket.

Fig. 16 is a diagram illustrating one method of operating the machine for the reclamation of comparatively loose material from the margin of a storage pile.

Fig. 17 is a cross section taken along the line XVII—XVII of Fig. 1.

Fig. 18 is a cross sectional view on the line XVIII—XVIII of Fig. 1.

Like numerals refer to similar parts in 95 the several figures.

As shown in the drawings my improved excavating machine comprises an elongated conveyer which is pivotally mounted upon a horizontal axis on an automobile truck. The 100 conveyer may be adjusted to various inclined positions or to a substantially horizontal position. The inclined positions are adapted to gather material from points in front of the machine at or near the ground 105 while the horizontal position is especially adapted for traveling under relatively low overhead obstructions.

The conveyer consists of a series of buckets 1 attached at spaced intervals to a pair of endless chains 2 which are adapted to travel around the foot wheels 3 and head wheels 4 supported at the opposite end of the conveyer frame upon the foot shaft 5 and head shaft 6 respectively. The foot wheels 3 are of larger diameter than the head wheels 4, for reasons which will be hereinafter explained. The conveyer frame comprises a structural steel framework having longitudinally extending angle bars 7 joined together by suitable cross members 8, 9 and 10. Attached to the side angles 7 near the center of gravity of the conveyer are steel plates 11 having apertures through which extends the supporting shaft 12 which is supported upon brackets 13 of the truck frame. To the under side of the cross members 8 and 9 are attached the steel straps 14 which form stirrups in which is slidably supported a wooden beam 15, formed of selected, straight grained timber, having a high coefficient of elasticity, and shaped to afford a resilient support for the gathering end of the conveyer. To the forward end of the beam 15 is bolted a suitable casting 16 to which the foot shaft 5 is attached and the foot wheels 3 are freely rotatable upon the shaft 5. Secured to the outer ends of the angle bars 7 are journal bearings 18 in which the head shaft 6 is mounted. To the head shaft 6 is attached a sprocket wheel 19 connected through a suitable driving chain 20 with the sprocket wheel 21 freely rotatable upon the projecting end of the pivot shaft 12. A sprocket wheel 22 formed integral with the wheel 21 is connected with the power devices of the machine to drive the conveyer in a manner to be hereinafter described.

Attached to the inner end of the beam 15 is a casting 23 having an aperture in which is screw threaded an adjusting screw 24 the outer end of which engages a socket 25 attached to the cross member 10. By manipulation of the screw 24 the beam 15 may be moved longitudinally in the stirrups 14 to adjust the tension of the conveyer chains 2 in a manner common in conveyer practice.

50 The chains 2 are of the well known type composed of side bars 26 connected by pintles 27. At spaced intervals certain of the side bars 26^a are provided with laterally extending flanges 28 to which the buckets 1 are secured by suitable attachment bolts.

Each of the buckets 1 is formed with a relatively long straight back 29 the lower part of which curves outwardly and upwardly to form the front wall 30 of the bucket. The front wall 30 is inclined upwardly at an acute angle with the back 29, and is connected thereto by side walls 31, 31 which are also inclined outwardly and upwardly to afford clearance for the heel of 60 the bucket relative to the material through

which it may be digging. At its upper end the front wall 30 is bowed outwardly, as shown in Fig. 15, and, together with the side walls 31, 31 is reinforced and protected by a renewable serrated steel bar 32 adapted to 70 cut and loosen relatively compact material. Owing to the extension of the serrated cutting bar 32 and to the peculiar form of the front wall 30 and side walls 31, the buckets are adapted to gather material from a relatively compacted mass either by a direct frontal advance or when advanced diagonally toward either side. The buckets 1 are so positioned upon the flanges 27 that the transverse plane extending perpendicular to the 80 longitudinal lines of the chain side bar 26^a through the axis of the rear pintle 27^a will also include the outermost edge of the front wall of the bucket. By so positioning the bucket upon the chains there is produced a 85 peculiar action at the foot and head of the elevator which greatly reduces the tendency for material to spill from the buckets during the operation of the conveyer.

In Fig. 11 is illustrated the action of a 90 bucket as it changes from the circular movement around the foot wheel to the straight line movement longitudinally of the conveyer. As the chain straightens out the front wall 30 of the bucket is rotated sharply 95 rearwardly about the pintle 27^a from the position shown by dotted lines at 30^a to the position shown by full lines at 30^b causing the included material to drop away from said front wall thereby settling said material into 100 the bucket and greatly reducing its tendency to spill over the edge of the bucket while in transit.

In Fig. 12 is illustrated the peculiar action of the bucket as it changes from the straight 105 line movement longitudinally of the conveyer to circular movement about the head wheel 4. As the chain wraps about the head wheel 4 the back wall 29 of the bucket is sharply rotated inwardly about the pintle 110 27^a, from the position indicated by dotted lines at 29^a to the position indicated by full lines at 29^b, causing said back wall to run away from the included material leaving 115 said material free to act under the influence of centrifugal force produced by its rotation about the head shaft 6. At the same time the movement of the front wall of the bucket from the position indicated by the dotted line 30^a to the position indicated by the full line 30^b produces an exhilaration in the material within the bucket which materially assists in its complete discharge. By this action the buckets are promptly and completely discharged of their loads thereby preventing the dribbling of material from the buckets of the return strand of the conveyer.

Owing to the relatively small diameter of the head wheels 4, a small lineal advance of the buckets as they pass over the head of the 130

conveyer causes a great angular advance thereby producing relatively great centrifugal force which assists in the discharge of material from the buckets. On the other 5 hand, the same lineal movement around the relatively large foot wheels 3 causes less centrifugal force and a proportionate decrease in the tendency of the buckets to throw material while gathering it.

10 To assist in dislodging firmly compacted material I have provided digging claws 33 interspersed with said buckets at suitable intervals upon the conveyer chains, and these digging claws are provided with renewable 15 cutter bits 34 adapted to engage the compacted material in a storage pile or natural deposit and tear it loose. By the devices above described my apparatus is adapted to reclaim firmly compacted material either 20 from natural deposits such as sand or gravel banks, or from storage piles such as the heaps of acid phosphate in fertilizer factories or the like. It is of course apparent that a greater or less number of digging claws may 25 be used, or they may be entirely omitted, to suit the requirements of the conditions under which the machine is operated.

When, from such causes as the freezing of the material, the buckets 1 and digging bits 30 34 are unable to penetrate the surface of the mass, the resilience of the beam 15 produces a beneficial ramming action. As the truck advances by the tractive effort of the wheels 39 and 40, the contact of the buckets 35 with the frozen material reacts against said traction and the inertia of the machine to produce a strain in the resilient beam 15 which causes the truck to rebound to be again advanced by the traction wheels. The 40 continuation of this action causes the conveyer buckets and digger bits to strike a succession of blows upon the material which drives said bits into the surface of the material and also tends to break it up.

45 In the operation of such machines it frequently happens that the forward end of the conveyer is completely buried by the avalanching of loose material. In such cases the resilience of the beam 15 permits it to yield 50 to the rearward pressure of the buckets as they advance around the foot wheel, thereby greatly relieving the strain upon the machine. This intermittent backward pressure of the buckets is transmitted, through the 55 beam 15, to the supporting truck forcing it rearwardly and thereby withdrawing the conveyer from the mass of loose material without the intervention of the attendant.

The supporting truck comprises a structural steel frame having bottom sill members 35 formed of suitable channel bars, to the forward ends of which are attached the upwardly extending angle bars 36, and these members are braced together with suitable 60 plates and angles in the manner well under-

stood by those well skilled in structural steel construction. The channel bars 35 rest upon and are rigidly attached to a square axle bar 37 at the ends of which are formed the spindles 38. Upon the spindles 38 are mounted 70 ground engaging traction wheels 39 and 40 which support the weight of the rearward part of the machine.

The angle bars 36 extend upwardly to form the brackets 13 upon which the conveyer frame is supported in the manner already described. To the angle bars 36 are attached the cross angles 41 and 42 and to these is attached the bracket casting 43. Formed in the bracket casting 43 in the 80 longitudinal central vertical plane of the machine is a journal bearing 44 in which is journaled the spindle 45 of the wheel fork 46. Formed on the bracket casting 43 is a stop 47 adapted to contact with the arms 85 of the fork 46 to limit its rotation. To the lower ends of the arms of said wheel fork is secured a spindle 48 upon which is journaled the ground engaging steering wheel 49 of relatively large diameter which supports the weight of the forward part of the machine. A worm wheel 50 on the spindle 45 is engaged by a worm 51 keyed to a transverse steering shaft 52. The shaft 52 is supported in suitable bearings 53 of the 90 bracket casting 43 and has at its outer end a hub 54 from which project radially extending arms 55 adapted to be grasped by the hand of the operator to rotate the shaft 52. By the rotation of the shaft 52 the spindle 100 48 may be turned in its bearing, thereby turning the plane of rotation of the ground wheel 49 to any desired angle with the longitudinal lines of the machine to steer it in any preferred direction. The worm 51 and 105 worm wheel 50 are of the non-overhauling type and serve not only to turn the steering wheel 49 but also to lock it in any preferred angular relation.

Mounted upon the channel bars 35 is a self contained power transmission mechanism having a frame comprising the side plate castings 56 and 57 in which are formed suitable journal bearings to support the several shafts of the transmission mechanism. The 110 frame castings 56 and 57 are held in spaced relation by the brace rod 58 secured in apertures of said castings, and by the steel shelf plate 59. Supported by the shelf 59 of the truck frame is a suitable motor 60 which 115 may be of any preferred type adapted to the conditions under which the machine is operated. For the purpose of illustration I have shown an electric motor, which may be supplied with electric current from any convenient source of electric supply through any suitable flexible conductor, and which may be controlled by any preferred type of controlling mechanism. As these devices 120 are well known in the art and from no part 125 130

of the present invention their illustration and description is not thought to be required at this time. To the armature shaft of the motor 60 is secured a pinion 61 which 5 engages the master gear 62 keyed to the jack shaft 63. The jack shaft 63 extends across the machine and upon its projected end 64 outside of the frame casting 57 is positioned a sprocket wheel 65 adapted to be oper- 10 atively connected to the jack shaft through a suitable friction clutch 66. The sprocket wheel 65 is connected by a chain 67 with the sprocket wheel 22 through which the conveyer is actuated. A suitable operating lever 68 is provided for the manipulation of the friction clutch 66, and this lever is connected with a pull rod 69 which extends across the machine to a position convenient 15 to the hand of the operator.

20 Mounted upon the jack shaft 63 and adapted to free rotation thereon and sliding motion longitudinally thereof, is a quill 70 having clutch teeth 71 and 72 formed upon its opposite ends. The clutch teeth 71 25 are adapted, when the quill is in its extreme right hand position of longitudinal adjustment to engage similar teeth upon the hub of the master gear 62 to drive the quill at the same speed as the master gear. Keyed 30 to the jack shaft 63 is a pinion 73 which engages a spur gear 74 supported for free rotation upon the cross brace rod 58 of the transmission frame. Formed on the hub of the gear 74 is a pinion 75 which engages a 35 spur gear 76 freely rotatable upon the jack shaft 63. On the hub of the gear 76 is formed clutch teeth adapted to engage with the teeth 72 when the quill 70 is in its extreme left hand position of longitudinal 40 adjustment, thereby driving the quill 70 through the gears 73, 74, 75 and 76 at a speed greatly reduced from that of the master gear 62. A shifting lever 77 is provided by which the quill 70 may be moved 45 longitudinally of the shaft 63, and this lever is connected with a pull rod 78 which extends through the side casing of the truck frame to a position convenient to the hand of the operator. A spur gear 79 formed on 50 the quill 70 has a sufficiently elongated face to permit of the extreme longitudinal adjustment of said quill without causing said pinion to lose its engagement with certain driven gears hereinafter more fully set forth.

55 Supported in suitable bearings 80 and 81 of the transmission frame castings 56 and 57 is a driven shaft 82 which projects outside the frame at both sides of the machine. 60 Upon the right hand end of the shaft 82 and extending through the journal bearing 81 of the frame 57 is rotatably mounted a quill 83. To the shaft 82 and the quill 83 respectively are attached a pair of oppositely disposed similar bevel gears 84 and 85 which are simultaneously engaged by a plurality of bevel pinions 86 carried by the ring gear 87, forming a differential drive of a type well known in the art. The ring gear 87 is engaged by a spur pinion 88 70 mounted for free rotation upon the shaft 89 which is secured at both ends to the transmission frame castings. Mounted upon the shaft 89 is a spur gear 90 arranged to be connected with the pinion 88 through a 75 suitable friction clutch 91. The clutch 91 is provided with a shifting lever 92 of the usual type and this lever is connected with the pull rod 93 extending through the side wall of the casing to a position convenient 80 to the hand of the operator. Supported upon the shaft 89 is a yoke casting 94 having two stud shafts 95 and 96. Upon the stud shaft 95 is journaled a pinion 97 arranged to engage the spur gear 90, and upon 85 the stud shaft 96 is mounted a slightly smaller spur pinion 98 which is arranged to engage the pinion 97 but to avoid engagement with the spur gear 90. The stud shafts 95 and 96 are so positioned relative to the 90 shaft 89, and the relative diameters of the pinions 97 and 98 are such that when the yoke 94 is rotated about the shaft 89 either one of the pinions 97 or 98 may be brought into engagement with the pinion 79. By 95 this arrangement of gearing the gear wheel 90 may be driven from the pinion 79 through the pinions 97 and 98 in one direction, or through the pinion 97 alone in the opposite direction.

100 The yoke 94 is connected by a link 99 with an arm 100 supported upon the driving shaft 81. Upon the outer end of the arm 100 is formed a gear segment 101 adapted to engage the pinion 102 attached to a trans- 105 verse shaft 103. The shaft 103 projects through the transmission frame at the left hand side of the machine and is provided with an operating handle 104 by which said shaft may be rotated. The operating handle 110 110 is provided with a latch 105 adapted to engage suitably positioned apertures 106 in the frame casting to secure said operating handle in either of its positions of angular adjustment. By manipulation of the oper- 115 ating handle 104 the yoke 94 may be rotated about its support to cause either of the pinions 97 or 98 to engage the pinion 79 to cause the reversal of the direction of the rotation of the drive shaft 82. Attached 120 to the drive shaft 82 and the quill 83 outside the frame of the machine are the pinions 107 and 108 which engage the ring gears 109 and 110 attached to the traction wheels 39 and 40 and through which power 125 is applied to propel the machine.

130 By the arrangement of rods and levers above described all of the devices for the control of the machine are made easily accessible from a position at one side of the

machine where the operator may conveniently observe the action of the conveyer. Through the agency of the rod 93 the truck may be gently started or stopped, and slip-
5 page of the friction clutch 91 affords protection to the transmission gearing in case the machine encounters an insurmountable ob-
struction. By the rod 78 the speed of travel may be controlled, and by the handle 104 its
10 direction may be reversed. By the spider arms 55 the truck may be steered in any preferred direction while the differential gear 87 permits the driving wheels 39 and 40 to properly function while the machine is
15 traveling in a curved path.

To effect the rotation of the conveyer about its pivotal support I have provided at each side of the machine a toggle lever which also serves to hold the conveyer in
20 any preferred position of angular adjustment. Both of the toggle levers comprises a bar 111 connected at its upper end to the side angle 7 of the conveyer frame by a suitable pivot bolt 112, and a bar 113 the lower
25 end of which is connected to the truck frame by a pivot bolt 114. The adjacent ends of the bars 111 and 113 are hinged together by a suitable hinge rod 115 which extends across the machine and maintains the spaced
30 relation of the toggle levers. Connected to the toggle levers by the hinge rod 115 are rack bars 116 formed of steel tubes having spaced alined apertures 117 adapted to engage with the teeth of the pinions 118. The
35 pinions 118 are keyed to a transverse shaft 119 which is supported in suitable journal bearings 120 and 121 attached to the angles 122 of the truck frame. Positioned at each side of each of the pinions 118 are journal
40 bearings 123 which are formed on the yoke castings having cylindrical body portions 124 through which the rack bars 116 are longitudinally slideable. The relation of the cylindrical body 124 and the journal bearings
45 123 is such as to maintain operative engagement between the pinions 118 and the rack bars 116. Keyed to the shaft 119 outside of the journal bearings 120 is a radially ex-
tending lever 125 to which are secured two
50 pivot studs 126. Upon the studs 126 are mounted oppositely disposed pawls 127 and 128 adapted to simultaneously engage a ratchet disk 129 formed on the end of the journal bearing 120. The pawls 127 and
55 128 are provided with outwardly extending projections 130 which engage the opposite ends of a compression spring 131 to press said pawls against said ratchet disk and thereby lock the shaft 119 against rotation
60 in either direction. Freely rotatable upon the shaft 119 is a hand wheel 132 having a longitudinally extending finger 133 which projects through an aperture 134 in the lever arm 125 and between the pawls 127 and 128. When the hand wheel 132 is rotated in
65 either direction the finger 133 contacts with one of the pawls, as for example the pawl 127, lifting it out of engagement with the ratchet disk 129 to permit the rotation of the shaft in that direction. Such movement 70 of the hand wheel 132 causes the finger 133 to engage the lever 125 to rotate the shaft 119 and thereby move the rack bar 116. When the hand wheel 132 is released the spring 131 instantly returns the pawl 127 to 75 engagement with the ratchet disks 129 to again lock the shaft 119 against rotation in either direction, and prevent further movement of said rack bar, thereby securing the conveyer in the preferred position of an-
80 gular adjustment.

In operation the machine will usually be moved from place to place at its higher rate of travel the lower speed being intended for feeding the conveyer into the material 85 which is to be reclaimed. When the steering wheel 49 is turned at an angle with the longitudinal lines of the machine the projected line of its axis of rotation will intersect the projected line of the axis of rotation of the traction wheels at a point about which the machine will travel in a circular path. The location and proportions of the stops 47 is such as to limit the rotation of the steering wheel to prevent the intersection 90 of said axial lines from falling between the traction wheels. Should such intersection fall between the traction wheels movement of the machine about such point of intersection could only be attained by the revolution of the driving wheels in opposite directions, and differential gearing of the type 95 here illustrated would not be available for such driving.

In Fig. 16 I have shown one method of 105 operation which is especially advantageous for reclaiming loose material, such as coal or crushed stone, when stored in piles upon the ground. After the gathering end of the conveyer has been adjusted in suitable prox-
110 imity to the material to be reclaimed, the steering wheel 49 is turned to steer the machine in a curve of suitable radius, causing the forward end of the conveyer to sweep a circular path such as is indicated by the line 143. The advancing front wall 30 and side walls 31^a of the buckets are thus brought into contact with the storage pile to gather material therefrom. After the conveyer has traveled across a sufficiently wide face, the 115 reversing handle 104 will be turned to cause the reversal of the direction of rotation of the traction wheels, thereby swinging the conveyer in the opposite direction. The angle of the steering wheel should be so ad-
120 justed at each reversal of the direction of travel as to produce a sufficient advance of the machine to enable the buckets to reach as the material in the pile and to be filled as 125 they pass around the foot wheel 3.

By the peculiar arrangement of driving and steering wheels herein set forth the conveyer may be caused to gather material from a relatively wide front without seriously disturbing the point of delivery.

A further advantage derived from the arrangement above described is the attainment in a rigid truck construction of relatively low center of gravity and a three point support peculiarly adapted to use upon extremely irregular ground.

Attached to the toggle bars 111 by hinges 135, in position to receive material discharged from the conveyer buckets as they pass over the head of the conveyer, is a hopper 136 the lower end of which is closed by a pair of clam shell valves 139 controlled by the lever 140 positioned within convenient reach of the hand of the operator. A counterweight 141 attached to the lever 140 serves to hold the valves 139 in closed position. A hood 142 formed on the upper edge of the hopper 136 prevents the throwing of material beyond the top of the hopper as it is discharged from the buckets. Projecting forwardly from the lower part of the hopper 136 is a strut 137 adapted to impinge upon the rear wall 138 of the truck frame to hold said hopper upright under working conditions. As the conveyer rotates about its pivotal support the strut 137 slides upon the wall 138 preserving contact therewith and thus maintains the hopper in working relation with the conveyer during a considerable range of its adjustment. As the rack bars 116 are thrust rearwardly to rotate the conveyer to its horizontal position the hinge rod 115 contacts with the forward wall of the hopper, lifting the strut 137 away from the frame of the machine, pushing the lower end of the hopper rearwardly to preserve a sufficient elevation of the valves 139 while traveling, as shown in Fig. 4.

The material gathered by the conveyer will be discharged in a continuous stream and accumulated in the hopper 136. After a sufficient amount of material has been so accumulated the machine may be moved, under its own power, to any preferred discharge position, or a succession of convenient receptacles, such as wheelbarrows or the like, may be passed beneath said hopper and, by manipulating the valves 139, the accumulated material may be transferred to said receptacles as they are successively placed, without interrupting the action of the conveyer.

When the material in the pile 143 is so compacted that it will not slide upon itself to be gathered from the ground at the margin of the pile, it may become desirable to feed the conveyer longitudinally along straight lines into the mass. By such feeding a kerf is cut in the mass having a width

equal to that of the buckets. As the buckets 1 are wider than any of their supporting devices at the forward part of the conveyer, or than the steering wheel 49 or any of its mountings, such kerf will afford 70 a path along which the wheel 49 may advance until the material at the sides of said kerf, indicated by the lines 144 in Fig. 2 contact with the frame of the truck. After the machine has been so advanced there may 75 remain an overhanging portion such as is indicated at 145 in Fig. 1. This overhanging material may be cut away by the elevation of the forward end of the conveyer through the instrumentality of the hand wheel 132, after which the machine may be backed away from the pile, the gathering end of the conveyer lowered, and the machine advanced along new lines.

It is to be understood that the above described methods of operation are only typical of the various uses to which the machine is adapted and that wide variation may be made in the details of its construction without departure from the spirit of my invention.

What I claim is—

1. In a machine of the class described, the combination with a main frame supported upon laterally disposed traction wheels in the rear of its center of gravity and a centrally disposed steering wheel in advance of said center of gravity, means to actuate said traction wheels to propel the machine, self locking means to control said steering wheel to guide the machine, and a longitudinally extending conveyer supported upon said frame and adapted to gather material from points in advance of said steering wheel and convey it rearwardly to elevated discharge points as and for the purpose set forth.

2. In a machine of the class described, the combination with a main frame supported upon laterally disposed traction wheels in the rear of its center of gravity and a centrally disposed steering wheel in advance of said center of gravity, means to actuate said traction wheels to propel the machine, self locking means to control said steering wheel to guide the machine, and a longitudinally extending conveyer supported upon said frame adapted to gather material from points at or near the level of the ground in advance of said steering wheel and convey it rearwardly to elevated discharge points as and for the purpose set forth.

3. In a machine of the class described, the combination with a main frame supported upon laterally disposed traction wheels in the rear of its center of gravity and a centrally disposed steering wheel in advance of said center of gravity, means to actuate said traction wheels to propel the

machine, self locking means to control said steering wheel to guide the machine, and a longitudinally extending conveyer supported in the central vertical plane of said frame 5 and having buckets wider than the face of said steering wheel adapted to gather material from points in advance of said steering wheel and convey it rearwardly to elevated discharge points as and for the purpose set forth.

4. In a machine of the class described, the combination with a main frame supported upon laterally disposed traction wheels in the rear of its center of gravity and a centrally disposed steering wheel in advance of said center of gravity, means to actuate said traction wheels to propel the machine, self locking means to control said steering wheel to guide the machine, a longitudinally extending conveyer pivotally supported upon a transverse horizontal axis on said frame and adapted to gather material from points in advance of said steering wheel and convey it rearwardly to elevated discharge 20 points, and means to adjust the angular relation of said conveyer about its support as and for the purpose set forth.

5. In a machine of the class described, the combination with a main frame supported upon laterally disposed traction wheels in the rear of its center of gravity and a centrally disposed steering wheel in advance of said center of gravity, means to actuate said traction wheel to propel the machine, self locking means to control said steering wheel to guide the machine, a longitudinally extending conveyer pivotally supported midway its length upon a transverse horizontal axis on said frame and adapted to gather material from points in advance of the steering wheel and convey it rearwardly to elevated discharge points, and means to adjust the angular relation of said conveyer about its support as and for the purpose set forth.

45 6. In a machine of the class described, the combination with an automobile truck, of a longitudinally extending conveyer supported midway its length upon a transverse horizontal axis on said truck, and rotatable thereon from a substantially horizontal traveling position to an inclined operative position adapted to gather material from points at or near the ground, means to rotate said conveyer about said axis, and means to automatically lock said conveyer in any preferred position of angular adjustment.

7. In a machine of the class described, the combination with an automobile truck, of a longitudinally extending conveyer supported midway its length upon a transverse horizontal axis on said truck, and rotatable thereon from a substantially horizontal traveling position to an inclined operative position adapted to gather material from points at or near the ground, means to rotate

said conveyer about said axis, means to automatically lock said conveyer in any preferred position of angular adjustment, and means to accumulate material delivered by said conveyer and to discharge the same at the option of the operator.

8. In a machine of the class described, the combination with a supporting frame, of a conveyer pivotally supported midway its length upon a transverse horizontal axis on said frame, strut bars hinged together and having their respective outer ends pivotally connected with the conveyer frame and the supporting frame, and means to vary the angular relation of said strut bars to cause rotation of said conveyer about its axis.

9. In a machine of the class described, the combination with a supporting frame, of a conveyer pivotally supported midway its length upon a transverse horizontal axis on said frame, strut bars hinged together and having their respective outer ends pivotally connected with the conveyer frame and the supporting frame, means to vary the angular relation of said strut bars to cause rotation of said conveyer about its axis, and means to automatically lock said strut bars in any preferred angular relation.

10. In a machine of the class described, the combination with a supporting frame, of a conveyer pivotally supported midway its length upon a transverse horizontal axis on said frame, strut bars hinged together and having their respective outer ends pivotally connected with the conveyer frame and the supporting frame, means to vary the angular relation of said strut bars to cause rotation of said conveyer about its axis, and a hopper carried by said strut bars adapted to receive material from said conveyer.

11. In a machine of the class described, the combination with a supporting frame, of a conveyer pivotally supported midway its length upon a transverse horizontal axis on said frame, strut bars hinged together and having their respective outer ends pivotally connected with the conveyer frame and the supporting frame, means to vary the angular relation of said strut bars to cause rotation of said conveyer about its axis, and a hopper pivotally supported upon said strut bars in position to receive material from said conveyer.

12. In a machine of the class described, the combination with a supporting frame, of a conveyer pivotally supported midway its length upon a transverse horizontal axis on said frame, strut bars hinged together and having their respective outer ends pivotally connected with the conveyer frame and the supporting frame, means to vary the angular relation of said strut bars to cause the rotation of said conveyer about its axis, a hopper hinged to said strut bars in position to receive material from said conveyer, and

means to retain said hopper in upright position during the operation of the machine.

13. In a machine of the class described, the combination with a supporting frame, of a conveyor pivotally supported midway its length upon a transverse horizontal axis on said frame, strut bars hinged together having their respective outer ends pivotally connected with the conveyor frame and 10 the supporting frame, a rack bar connected with said hinge and engaging a pinion upon a control shaft by the rotation of which the angular relation of said strut bars may be varied to cause the rotation of said conveyor 15 about its axis.

14. In a machine of the class described, the combination with a supporting frame, of a conveyor pivotally supported midway its length upon a transverse horizontal axis on 20 said frame, strut bars hinged together having their respective outer ends pivotally connected with the conveyor frame and the supporting frame, a rack bar connected with said hinge and engaging a pinion upon a 25 control shaft by the rotation of which the angular relation of said strut bars may be varied to cause the rotation of said conveyor about its axis, and means to automatically lock said shaft against rotation in either 30 direction.

15. In a machine of the class described, the combination with a supporting frame, of a conveyor pivotally supported midway its length upon a transverse horizontal axis on 35 said frame, strut bars hinged together having their respective outer ends pivotally connected with the conveyor frame and the supporting frame, a rack bar connected with said hinge and engaging a pinion upon a 40 control shaft by the rotation of which the angular relation of said strut bars may be varied to cause the rotation of said conveyor about its axis, manually operated means to rotate said control shaft, and means automatically effective when said rotating means 45 is released to lock said shaft against rotation in either direction.

16. In a machine of the class described, the combination with an elongated conveyor 50 frame, of transverse head and foot shafts carried thereby, chain engaging wheels mounted upon said shafts, an endless chain mounted upon and adapted to travel around said wheels, said chain comprising a series 55 of longitudinally extending bars suitably articulated at their adjacent ends, conveyor buckets having relatively long straight back walls and upwardly and outwardly inclined front walls attached to said chain bars in 60 such relation thereto that the transverse plane extending perpendicularly to the length of said bar through the axis of its rear articulation will include the advancing edge of said front wall.

17. In a machine of the class described, the combination with an elongated conveyor frame, of transverse head and foot shafts carried thereby, chain engaging wheels mounted upon said shafts, an endless chain mounted upon and adapted to travel around said wheels, said chain comprising a series of longitudinally extending bars suitably articulated at their adjacent ends, conveyor buckets having relatively long straight back walls and upwardly and outwardly inclined front and side walls attached to said bars in such relation thereto that the transverse plane extending perpendicularly to the length of said bar through the axis of the rear articulation will include the advancing 80 edge of said front wall.

18. In a machine of the class described, the combination with an elongated conveyor frame, of transverse head and foot shafts carried thereby, chain engaging wheels 85 mounted upon said shafts, an endless chain mounted upon and adapted to travel around said wheels, said chain comprising a series of longitudinally extending bars suitably articulated at their adjacent ends, conveyor 90 buckets having upwardly and outwardly inclined front walls attached to said chain bars in such relation thereto that the transverse plane extending perpendicularly to the length of said bar through the axis of its 95 rear articulation will include the advancing edge of said front wall.

19. In a machine of the class described, the combination with an elongated conveyor frame, of transverse head and foot shafts 100 carried thereby, chain engaging wheels mounted upon said shaft, an endless chain mounted upon and adapted to travel around said wheels, said chain comprising a series of longitudinally extending bars suitably 105 articulated at their adjacent ends, conveyor buckets having upwardly and outwardly inclined front and side walls attached to said chain bar in such relation thereto that the transverse plane extending perpendicularly to the length of said bar through the axis of its 110 rear articulation will include the advancing edge of said front wall.

20. In a machine of the class described, the combination with a supporting frame, of a longitudinally extending resilient conveyor frame projecting forwardly from said supporting frame, and a conveyor mounted upon said conveyor frame as and for the purpose set forth.

21. In a machine of the class described, the combination with a supporting frame, of a longitudinally extending resilient conveyor frame projecting forwardly from said supporting frame, and a conveyor mounted upon said conveyor frame and adapted to gather material from points in advance thereof and convey it rearwardly to ele- 120 125

vated discharge points as and for the purpose set forth.

22. In a machine of the class described, the combination with a supporting frame, of 5 a longitudinally extending resilient conveyer frame supported upon a transverse horizontal axis on said supporting frame, and a conveyer mounted upon said conveyer frame adapted to gather material from 10 points in advance thereof and convey it rearwardly to elevated discharge points as and for the purpose set forth.

23. In a machine of the class described, the combination with a supporting frame, 15 of a longitudinally extending conveyer frame supported upon a transverse horizontal axis on said supporting frame the forward part of said conveyer frame being resilient for movement in longitudinal vertical planes, and a conveyer mounted upon 20

said conveyer frame as and for the purpose set forth.

24. In a machine of the class described, the combination with a supporting frame, of a longitudinally extending conveyer 25 frame pivotally supported midway its length upon a transverse horizontal axis upon said supporting frame the forward part of said conveyer frame being resilient means to adjust the angular relation of said 30 conveyer about its support, and a conveyer mounted upon said conveyer frame as and for the purpose set forth.

In testimony whereof, I affix my signature, in presence of two witnesses.

WILLIAM K. LIGGETT.
